UNITED STATES PATENT OFFICE.

EARLE B. LEWIS, OF WATERBURY, CONNECTICUT.

RADIO RECEIVING SYSTEM.

Application filed August 8, 1922. Serial No. 580,455.

To all whom it may concern:

Be it known that I, EARLE B. LEWIS, a citizen of the United States, and a resident of Waterbury, county of New Haven, and 5 State of Connecticut, have invented certain new and useful Improvements in Radio Receiving Systems, of which the following is a specification.

This invention relates to a system for amplifying and detecting high frequency electromagnetic waves, and more particularly to 10 a radio receiving system having an audion detector.

One object of this invention is to provide 15 means for permitting increased amplification of the received signals of a radio frequency set.

A further object is to eliminate the undesired locally generated "feed-back" currents 20 originating in the audion and other parts of the circuit, by suppressing such locally generated oscillations and thus preventing them from building up to an injurious degree.

A further object is to selectively absorb 25 the energy of such undesired locally generated oscillations, and to dissipate such energy in the form of heat without materially absorbing the energy of the desired oscillations.

30 A further object is to provide a receiving system of the above nature in which means are provided for tuning the energy absorbing means to the frequency of undesired waves.

A further object is to provide a device of 35 the above nature which will be simple, easy to manipulate, cheap to manufacture, comparatively fool-proof, and very efficient and durable in use.

With these and other objects in view, there 40 have been illustrated on the accompanying drawing several forms in which the invention may be conveniently embodied in practice.

Fig. 1 represents a diagrammatic view of 45 a complete radio-receiving system, having one form of the present invention embodied therein.

Fig. 2 is a diagrammatic view of a portion 50 of the system shown in Fig. 1 showing a modified form of the invention applied thereto.

Fig. 3 is a diagrammatic view, similar to Fig. 2, showing in perspective another form 55 in which the invention may be embodied.

Fig. 4 is a detailed perspective view of the

adjustable metal band of the modification shown in Fig. 3.

In the reception of radio waves it has been found that objectionable disturbing noises such as are due to variations in the batteries 60 are less highly amplified when operating at radio-frequency than when operating at audio-frequency. For the above and other reasons it is desirable in wireless receiving sets to amplify as much as possible at radio- 65 frequency.

Up to the present time, however, considerable difficulty has been experienced with wireless receiving sets operating with radio-frequency particularly at short wave- 70 lengths. This difficulty has been chiefly caused by the locally generated "feed-back" oscillations in the grid circuit which interfered with the reception of the desired waves sent out by the transmitting or 75 "broadcasting" station and often drowned them out altogether. These locally generated oscillations were caused principally by the capacity coupling which exists between the grid and plate of the audion. This 80 caused the grid circuit to become "unstable", especially when the successive stages of the set were "transformer coupled."

According to the present invention, a 85 radio-frequency receiving set has been provided, in which the above and other disadvantages have been largely, if not entirely, avoided. This has been accomplished by employing means external to the grid circuit and coupled to the inductance of said grid 90 circuit adapted to be tuned into resonance with the undesired locally generated oscillations and which will absorb them selectively 95 without affecting the desired waves being received through the antenna.

Referring now to the drawings in which like reference numerals denote corresponding parts throughout the several views, the numeral 10 represents a receiving antenna of a wireless receiving system. The radio 100 waves received by the antenna 10 pass through a variable condenser 11, an inductance coil 12, which is also preferably variable, a ground wire 13 to the ground 13^a.

The grid circuit of the first stage of amplification comprises a conducting wire 14, a grid 15, an incandescent filament 17, wire 18^a, and wire 18^b the latter being connected to the antenna circuit between the inductance coil and the ground wire 13. The 110

grid 15, the filament 17, and plate 18 are mounted as usual in an evacuated audion tube 16.

In order to connect the first stage of amplification to the second stage, the plate 18 of the audion 16 is connected to a primary coil 19 of a transformer 20. The primary coil 19 is inductively coupled to the secondary coil 21 which is located in the grid 10 circuit of the second stage.

The amplified oscillations from the second stage are next rectified and converted to audio-frequency oscillations in the third stage or detector 30 of the set. The plate 15 24 of the second stage is connected to a primary coil 25 of a second transformer 26, the primary coil 25 being inductively coupled to a secondary coil 27 in the third stage. A grid condenser 28 is employed in this stage 20 between the secondary coil 27 and the grid 29.

The audio-frequency oscillations from the third stage or detector 30 are converted into audible sound waves by means of a telephone 25 receiver 30^a which is located between the plate 31^a and the B battery of the detector 30 plate circuit. It will be understood of course that a loud speaker may be substituted for the telephone receiver within the spirit of 30 the invention.

As clearly shown in Fig. 1, the audion plates 18 and 24 of the radio-frequency stages are connected to a bus-bar 31^b leading to the positive terminal of the B battery 35 shown at the right of the figure. Each of the audion filaments 17, 23, and 31 are connected to the bus-bars 32 and 33 leading to the positive and negative terminals respectively of the A battery, adjustable rheostats 40 34, 35 and 36 being provided to enable the temperature of the filaments to be separately controlled.

The device for selectively absorbing the energy of the undesired oscillations of the 45 grid circuit will next be described. This device, as herein disclosed, comprises an exterior closed circuit inductively coupled with the induction coil 12. In the form shown in Fig. 1, an inductance coil 37 is provided and 50 is shunted by a variable condenser 38, by means of which the closed circuit may be tuned into resonance with the undesired oscillations of the grid circuit of the first stage. In the modified form of energy absorbing 55 device illustrated in Fig. 2, a rheostat 39 is employed as the tuning means, instead of the variable condenser 38 illustrated in Fig. 1.

In the operation of the systems illustrated 60 in Fig. 1 and Fig. 2, the inductive closed circuit will first be tuned into resonance with the locally generated oscillations of the grid circuit. The grid circuit will next be tuned into resonance with the desired waves being 65 sent out by the transmitting station. This

may be accomplished by suitably adjusting the variable condenser 11.

When the exterior inductive closed circuit has been properly adjusted it will act as an absorbing device for the undesired vibrations 70 of the grid circuit, said vibrations being dissipated as heat in the exterior closed circuit.

In Figs. 3 and 4, a still further form of energy absorbing device is illustrated. In this form, a circular closed metal band 40 is 75 rotatably mounted within a ring 41 formed on the end of the coil 12. The band 40 is provided with a shaft 42 whose axis is at right angles to the axis of the coil 12. The shaft 42 has a pair of bearing portions 43 80 and 44 adapted to fit within suitable apertures in the ring 41, and is provided with a knob 45 whereby the band 40 may be easily rotated to vary the inductive effect. In practice the dimensions and shape of the 85 band 40 will be chosen so that it will be in resonance with the undesired oscillations of the grid circuit, and it will absorb such oscillations in the same manner as the devices 90 illustrated in Figs. 1 and 2.

One important advantage of the present invention is that the absorption of the undesired locally generated energy will be accomplished without materially diminishing 95 the intensity of the received oscillations.

Another advantage is that the absorption of such energy will prevent the undesired oscillations from "building up" to an injurious degree, even when the successive stages 100 of the set are transformer coupled, and consequently a higher degree of amplification may be secured without making the tubes unstable.

While the means for absorbing undesired oscillations has been illustrated only in the 105 first stage of a radio-frequency system, it will be understood that it may also be applied to other stages of this system or in any other systems in which it is desired to absorb the high-frequency oscillations.

While there have been disclosed in this specification several forms in which the invention may be embodied, it is to be understood that these forms are shown for the purpose of illustration only, and that the 115 invention is not to be limited to the specific disclosures, but may be modified and embodied in various other forms without departing from its spirit. In short, the invention includes all the modifications and embodiments coming within the scope of the 120 following claims.

Having thus fully described the invention, what is claimed as new, and for which it is desired to secure Letters Patent, is:

1. In an audion radio receiving system, a grid circuit, an audion tube, an absorbing device for the undesired oscillations fed back into said grid circuit from said audion tube comprising an inductance coil in said grid 120

5 circuit, said coil including an outer stationary metallic ring in series therewith, an inner closed ring located within said outer ring and mounted on an axis which is in the plane of said outer ring, said inner ring being adapted to be rotated on its axis whereby the energy of said oscillations will be selectively absorbed by induction and dissipated as heat.

10 2. In an audion radio receiving system, a grid circuit, an audion tube, an absorbing device for the undesired oscillations fed back into said grid circuit from said audion tube comprising an inductance coil in said grid

15 circuit, said coil including an outer stationary metallic ring in series therewith, an inner closed ring located within said outer ring and mounted on a shaft which is in the plane of said outer ring, said inner ring being adapted to be rotated on its axis whereby 20 the energy of said oscillations will be selectively absorbed by induction and dissipated as heat, said inner ring comprising a band of thin metal, rigidly mounted on said shaft.

25 In testimony whereof, I have affixed my signature to this specification.

EARLE B. LEWIS.
